(57) **CLAIM**

The ornamental design for a wound dressing, as shown and described.

DESCRIPTION

FIG. 1 is a perspective view showing the new design of a first embodiment of a wound dressing;

FIG. 2 is a top view thereof;

FIG. 3 is a bottom view thereof;

FIG. 4 is a front view thereof, the rear view being a mirror image thereof;

FIG. 5 is a right side view thereof, the left side being a mirror image thereof;

FIG. 6 is a perspective view showing the new design of a second embodiment of a wound dressing;

FIG. 7 is a top view thereof;

FIG. 8 is a bottom view thereof;

FIG. 9 is a front view thereof, the rear view being a mirror image thereof; and,

FIG. 10 is a right side view thereof, the left side being a mirror image thereof.

The surface shading illustrated in the drawings is provided merely to highlight the contour of the design and indicate the opacity and transparency/translucency of its components; and is not intended to be illustrative of texture or gloss.
